LOCKING DEVICE FOR TWO RELATIVELY
DISCONNECTABLE PARTSAbraham de Vries, Amsterdam, Netherlands, as-
signor to Naamlooze Venootschap Ijzerhandel
I. M. de Vries, Amsterdam, NetherlandsApplication January 19, 1935, Serial No. 2,565

3 Claims. (Cl. 292—244)

This invention relates to locking means which enables relatively movable parts to be connected together and disconnected without it being necessary to open the casing in which they are fitted 5 and without requiring a device operable from the outside to remove the coupler.

To effect the reversal of two parts relatively to one another, hitherto it has been necessary either to open the casing containing the locking device 10 or to provide means operable from outside the casing and requiring a special tool for the purpose.

The device according to the invention may be applied, for instance, to a door-lock, in which case the lock bolt, in order to make the latter 15 reversible so as to adapt the lock for either right-hand or left-hand closing doors, is formed in two disconnectable parts, these parts being provided with a locking member by which means the outwardly extending part of the lock bolt can 20 be withdrawn from the casing, reversed and re-connected.

In one arrangement of the device as applied to a door-lock, the locking bolt is formed in two parts, which latter are adapted to be connected 25 together by means of a coupling or locking pin which is a freely movable body. This pin under the action of gravity may be moved from the locking position into a position in which the two parts are disconnected, whereby the projecting bolt portion can be withdrawn from the casing, 30 reversed, replaced into position and reconnected to the other portion.

In order that the invention may be clearly understood reference will now be made to the accompanying drawing in which Fig. 1 illustrates a constructional example of a locking device applied 35 to a door-lock. Only that part of the lock is shown to which the invention relates, the covering plate being removed; Figs. 2 and 3 are fragmentary views of two modifications of the arrangement shown in Fig. 1.

The casing 1 of the lock is connected to the front plate 2 which is provided with an aperture 3 through which the forepart of the locking bolt 4 45 extends outwardly. This part 4 is provided with an inwardly extending portion 5 provided with a transverse bore 6. In the shown position the portion 5 is fitted in a bore 7 of the afterpart 8 of the locking bolt. In this part 8 a chamber 9 50 is formed which represents the elongation of the transverse bore 6 in the portion 5 of the locking bolt.

In this chamber 9 a free coupling pin 10 may be inserted longitudinally (after which the entrance 55 is closed by solder or otherwise) whereby

said pin 10 in the position shown connects the two parts 4 and 8 of the locking bolt together in such a way that (in consequence of the corresponding dimensions of the chamber 9, the pin 10 and the transverse bore 6) the two parts can 5 only move together.

When it is desired to reverse the lock bolt, the lock as a unit is turned upside down. In this position the pin 10 in the chamber 9 falls to such an extent that the coupling, between the two lock bolt parts 4 and 8, is removed. It is then possible to withdraw the part 4 of the lock bolt outwards so that it may be turned to the reversed position with regard to the part 8. When in this position the pin portion 5 of the part 4 15 is inserted again in the bore 7, the pin 10, after again reversing the entire lock to the upright position, falls again into the bore 6 whereby the coupling of the two lock bolt parts is again obtained.

The pin 10 may also be made bipartite, whereby the longitudinal dimension of the chamber 9 may be reduced.

In the bore 7 of the part 8 of the locking bolt is another pin 11 which is pressed against the pin 5 by a plate-spring 13 reaching into a recess 12 in pin 11. After the coupling has been removed in the manner described and the lock bolt part 4 with the pin 5 is drawn out of the lock, the plate-spring 13 pushes the pin 11 so far into 30 the bore 7 that the chamber 9 is closed and the enclosed pin 10 cannot return to the locked position until by the insertion of the pin 5 the pin 11 is again pushed back. It is desirable to form the chamber 9 likewise as an elongation on 35 the other side of the bore 6, whereby the pin 10 in the locked position extends on both sides beyond the pin 5.

In a modification, as shown in Figure 2, instead of the single locking pin 10 as in Figure 1, this 40 pin is formed in two parts 10 and 10a, the chamber 9 being of such a depth that, when the lock unit is turned upside-down, the portion 10 falls into the chamber 9 while the part 10a being situated in the transverse bore, the part 4 of 45 the locking bolt can be withdrawn.

In the further modification shown in Figure 3, instead of the pin 10, the freely movable body may comprise a ball, indicated by 10b which is 50 arranged as the coupling member. The recess or chamber 9 above the ball 10b is sufficiently deep that when the unit is turned upside-down the ball drops clear of the pin 5 which latter can then be withdrawn. Corresponding recesses are 55

formed on opposite sides of pin 5 into which ball 10b can engage.

Having now described my invention, what I claim as new and desire to secure by Letters 5 Patent is:—

1. A locking device comprising a bipartite lock bolt, one part having a bore therethrough and the second part having a stem engaged in said bore with a hole passing laterally through the 10 stem and continued axially as a recess in the first part of the bolt, and a freely movable body within said hole and recess.

2. A locking device comprising a bipartite lock bolt, one part having a bore therethrough and 15 the second part having a stem engaged in said

bore with a hole passing laterally through the stem and continued axially as a recess in the first part of the bolt, and a freely movable pin within said hole and recess.

3 A lock for doors and the like comprising a 5 bipartite lock bolt, one part having a bore therethrough and the second part having a stem engaged in said bore with a hole passing laterally through the stem and continued axially as a recess in the first part of the bolt, a freely mov- 10 able body within said hole and recess, a second pin that is engaged in the bore and abuts the end of the stem and a spring with its free end engaging with the second pin.
